UNITED STATES PATENT OFFICE

120,112

DESIGN FOR A CUP HANDLE ALPHABET OR SIMILAR ARTICLE

Aage Schmidt, Highland Park, Ill.

Application January 5, 1939, Serial No. 82,162

Term of patent 14 years

To all whom it may concern:

Be it known that I, Aage Schmidt, a citizen of the United States, residing at Highland Park, in the county of Lake and State of Illinois, have invented a new, original, and ornamental Design for a Cup Handle Alphabet or Similar Article, of which the following is a specification, reference being made to the accompanying drawings, forming a part thereof.

On the drawings, Figs. 1—A to 1—Z, inclusive, are side elevational views of a cup handle alphabet showing my new design;

Fig. 2 is a side perspective view of Fig. 1—A illustrating the third dimension.

I claim:

The ornamental design for a cup handle alphabet or similar article, substantially as shown.

AAGE SCHMIDT.
